UNITED STATES PATENT OFFICE

91,938

DESIGN FOR A TRAILER

George R. Goin and Bruno A. De Polo,
Detroit, Mich.

Application August 18, 1933, Serial No. 49,056

Term of patent 14 years

To all whom it may concern:

Be it known that we, GEORGE R. GOIN and BRUNO A. DE POLO, citizens of the United States, residing at Detroit, Wayne county, Michigan, have invented a new, original, and ornamental Design for Trailers, of which the following is a specification, reference being had to the accompanying drawings forming part thereof, wherein:

Fig. 1 is a top plan view of a trailer embodying the new design.

Fig. 2 is a view of the same in side elevation.

Fig. 3 is a front view thereof.

Fig. 4 is a rear view.

The illustrated trailer is the stream-lined, closed body type intended for either commercial or camping use.

I claim:

The ornamental design for a trailer, as shown and described.

GEORGE R. GOIN.
BRUNO A. DE POLO.
